UNITED STATES PATENT OFFICE.

HARRY EHLIG, OF PEARL RIVER, NEW YORK, ASSIGNOR TO GEORGE B. SWART & COMPANY, INC., OF NEW YORK, N. Y., A CORPORATION OF NEW YORK.

SHEET FEEDER.

Application filed October 28, 1924. Serial No. 746,346.

My invention relates more particularly to certain novel improvements or attachments in sheet-feeding mechanism employing pneumatic means for automatically separating and forwarding successive sheets of paper to printing, folding or ruling machines, or to other types of machines devised thereafter to operate on such sheets.

The objects of my invention are, among other things, to provide a novel and simplified control for the pneumatic suction wheel used to separate and forward the successive sheets so as to vary the intermittent action of the wheel in withdrawing and advancing such sheets, which control may be manually adjusted and regulated to vary the extent of the spacing of sheets of different sizes or lengths. Heretofore in front-edge sheet-feeders embodying a revolving perforated suction feed-wheel for feeding the sheets forwardly from either a vertical pile or a bank of fanned-out sheets, such revolving suction wheel has been rotated at a constant peripheral speed with the variable spacings between the successive sheets controlled by the variable intermitting of the suction applied to the perforated rim of the continuously revolving suction-wheel. My improved attachment provides a manual control of the velocity or peripheral speed of the suction feed-wheel so as to vary thereby the extent of the spacings between the sheets by varying the peripheral speed of the wheel itself without in any way affecting the customary mechanism used to intermit the suction applied to such wheel to space the successive sheets.

My improved sheet-feeder also embodies other novel features and improvements by which the separation and feeding mechanisms are simplified and made more effective and otherwise better adapted for use, all of which will be hereinafter described and then particularly pointed out in the appended claims.

Of the drawings, Fig. 1 is a top plan view of a portion of the feeder showing the suction feed-wheel and conveyor tapes together with the mechanism devised for regulating the peripheral speed of the feed-wheel;

Fig. 2 is a side elevation of Fig. 1;

Fig. 3 is a section taken on the line 3—3 of Fig. 2; and

Fig. 4 is a section taken on the line 4—4 of Fig. 2.

Similar numerals refer to similar parts throughout the several figures.

Referring to the drawings, the side-frame 5 supports the feed-board 6 upon which the sheets 7 rest preparatory to separation, as shown in Fig. 1, the opposite side frame not being illustrated. In the present embodiment the sheet separating and feeding mechanism comprises the suction feed-wheel 8 (Figs. 1 and 2) the peripheral rim 9 of which is formed with a series of spaced-apart perforations 10 throughout, which wheel 8 is mounted on the shaft 11 journalled in the side-frame 5. The outer end of the shaft 11 carries the cone-pulley 12 around which passes the belt-band 13 which in turn passes around the oppositely-coned pulley 14 journalled on the stub shaft 15 fastened to the lever 16 pinned on the shaft 17 secured to the side-frame 5 as shown in Figs. 2 and 3. The rear end 18 of the lever 16 is formed with the arcuate slot 19 through which the threaded bolt 20 secured to the frame 5 passes with the nut 21 fastened to the bolt end. By adjusting the lever 16 vertically on the shaft 17, any slack or tension of the belt-band 13 may be regulated. Fastened to the pulley 14 is the gear 22 which meshes with the gear 23 journalled on the shaft 17. Secured to the gear 23 is the sprocket 24 around which passes the drive chain 25 which in turn passes around the sprocket 26 fastened to the outer end of the drive shaft 27 on which is mounted the lower feed-roll 28, around which pass the sheet conveyor tapes 29. By this mechanism the suction feed-wheel 8 is constantly rotated to separate the sheets 7 and advance same to the conveyor tapes 29 between the lower feed roll 28 and the upper rollers 30, the wheel 8 revolving in an anticlockwise direction (Fig. 2).

The suction mouth piece 31 rests on the inner face of the perforated rim 9 and is connected to the transverse suction tube 32 by the pipe 33 as shown in Fig. 1. The required suction to operate the wheel 8 to enable it to pick up and separate the sheets on the feed-board 6 is applied to the tube 32 from the hose 34 connected with any suitable air-exhausting device not shown. Since these parts are common forms of printing machinery construction and are well known in the art, they need not be more fully described, it being sufficient to note that the

successive sheets are separated and fed forward by the suction feed-wheel 8 onto the lower feed-roll 28 from which the sheets are thereafter carried forwardly by the conveyor tapes 29 in the usual way.

The mechanism for varying and controlling the velocity or peripheral speed of the feed-wheel 8 may be widely varied in construction and operation. In the present embodiment I have shown a simple and effective means for manually shifting the belt-band 13 inwardly or outwardly on the cone-pulleys 12 and 14 so as to regulate the velocity of the shaft 11 on which the feed-wheel 8 is mounted. Referring to Figs. 1, 2 and 4, the inner end of the threaded bar 35 is journaled into the side-frame 5 and has the washer nuts 36 and 37 affixed thereto on either side of the frame 5 as shown in Fig. 4. The looped shifting plate 38 is slideable inwardly and outwardly on the guide bar 39 fastened to the side-frame 5 as the threaded bar 35 is rotated. The plate 38 encloses the belt-band 13 between the spaced-apart ends 40 as shown in Fig. 2. The lower right-hand end of the plate carries the lug 41 having a threaded bore coacting with the bar 35 as shown in Fig. 4, while the outer end of the bar 35 has pinned thereto the hand-crank 42 to rotate the bar 35 in either direction so as to shift the plate 38 inwardly or outwardly as required.

The operation of my attachment for varying the peripheral speed of the suction-wheel 8 is substantially as follows: While the wheel is revolving at a predetermined speed by the mechanism heretofore described, the spacings between the sheets 7 is constant. Should the operator desire to increase or diminish the spacings between the sheets to time same with the printing, folding or ruling machine, all that is necessary is to revolve the hand-crank in one direction or the other to thereby shift the plate 38 transversely on the guide bar 39 which movement carries and then maintains the belt-band 13 in any predetermined position along the inclined peripheral surfaces of the cone-pulleys 12 and 14. Such sidewise movement of the band 13 on the pulleys 12 and 14 increases or diminishes the velocity of the rotatable

shaft 11 and so regulates the peripheral speed of the perforated rim 9 of the wheel 8 whereby the relative spacings between the fed-off sheets may be readily and effectively 55 adjusted and controlled by the operator without interfering in any way with the mechanism employed for intermitting the suction applied to the rim 9.

The foregoing construction embodies the 60 principles of my invention, but various changes may be made in the structural details without departing from the scope of my improvements. However, the foregoing is sufficient to disclose the underlying principles and advantages as embodied in a suction sheet-feeder.

I claim as my invention:

1. In a sheet-feeder, a suction feed-wheel having a perforated rim, a suction nozzle for applying pneumatic suction to the lowest portion of the rim to separate the successive sheets, means for rotating said feed-wheel, conveyor tapes moving at a uniform speed for forwarding the successive separated sheets from said feed-wheel, and a single mechanism for directly effecting differential revolutions to said wheel rotating means relatively to the speed of said conveyor tapes while the feeder is in operation, whereby 80 the spacings between the separated sheets may be varied without affecting the suction applied to wheel rim through said suction nozzle.

2. In a sheet-feeder, a suction feed-wheel 85 having a perforated rim, a suction nozzle for applying pneumatic suction to the lowest portion of the rim to separate the successive sheets, means for rotating said feed-wheel, conveyor tapes moving at a uniform speed 90 for forwarding the successive separated sheets from said feed-wheel, and a single mechanism controlled by the operator for directly effecting differential revolutions to said wheel rotating means relatively to the 95 speed of said conveyor tapes while the feeder is in operation, whereby the spacings between the separated sheets may be varied without affecting the suction applied to wheel rim through said suction nozzle.

HARRY EHLIG.
